SAND TRAP

Guilford S. Turner, Berwyn, Ill., assignor to
 Morris B. Brewster Co. Inc., Chicago, Ill., a
 corporation of Illinois

Application May 20, 1940, Serial No. 336,157

3 Claims. (Cl. 291—11)

The invention relates generally to track sanding apparatus used on locomotives.

In sand-traps for locomotives, it is desirable to provide an air-nozzle which may be adjusted to vary the quantity of sand discharged from the trap. In the constructions heretofore used, the connection for supplying air to the sand-trap was axially aligned with the nozzle and required disconnection from the sand-trap to provide access to the nozzle for adjustment of the nozzle. When the coupling for the air delivery pipe to the trap was disconnected it frequently occurred that the coupling would not be securely tightened and the supply of air into the trap would be inadequate or would not be at the predetermined rate.

One object of the invention is to provide an improved sand-trap in which the air delivery nozzle is adjustable and can be adjusted to vary the rate of delivery of air into the trap without requiring uncoupling of the air-supply pipe from the trap.

Another object of the invention is to provide a construction in which the restricted port, through which the air is delivered to the nozzle, is disposed in a plug which can be removed from the trap without uncoupling the air supply pipe from the trap.

Another object of the invention is to provide an improved air delivery nozzle which is provided with improved means for restricting the air discharged into the trap to expel the sand.

Other objects of the invention will appear from the detailed description.

The invention consists in the several novel features which are hereinafter set forth and are more particularly defined by claims at the conclusion hereof.

In the drawing:

Fig. 1 is a vertical longitudinal section of a sand-trap embodying one form of the invention.

Fig. 2 is a section taken on line 2—2 of Fig. 1.

Fig. 3 is a perspective of the air nozzle.

Fig. 4 is a perspective of the plug for closing the opening which provides access to the nozzle.

Fig. 5 is a longitudinal section of a sand-trap embodying a modified form of the invention.

Fig. 6 is a longitudinal section of the nozzle shown in Fig. 5.

The track-sander is of the type used on locomotives and comprises a sand-trap which receives sand from a sand-box or dome on top of the locomotive and is supplied with air under pressure from the usual compressed air supply for discharging the sand, a pipe for delivering

sand to the rail or rails adjacent one or more of the wheels on the locomotive. In the construction shown in Figs. 1 to 4, the sander comprises a body or casing 10 which is formed with a vertical extension 12 which is connected by a union-coupling 13 to the pipe 14 which delivers the sand from the sand-box. The sand from pipe 14 passes through the inlet 15 in extension 12 and into the horizontally extending trap-conduit 16 in the casing which extends laterally from said inlet. At the opposite end, casing 10 has connected thereto a pipe 17 for delivering sand to the rails. An air duct 18 is formed in the casing to direct a clean-out blast into and through pipe 17 at the beginning and the end of each sanding operation under control of a suitable valve, as is well understood in the art. A pipe 19 is connected to casing 10 to deliver air under pressure to duct 18. A removable screw-plug 12^c is provided in the bottom of the casing 10 for access to the sand in the extension 12.

A nozzle 20, having its axis extending longitudinally of the trap-conduit 16, is adapted to direct air under pressure through said conduit to deliver the sand to and force it through the pipe 17 which delivers the sand to the rails. This nozzle comprises a tubular discharge member 21, which extends into conduit 16 and is provided with an integral head 22. The nozzle is supported in a boss 23, which is integral with and extends inwardly from the wall at the elbow of the casing 10. Head 22 has a screw thread 24 which fits into a screw-threaded socket 25 formed in boss 23. The inner end of boss 23 is provided with a cylindrical opening, through which member 21 of the nozzle extends, and in which it is slidable and rotatable. The outer end of head 22 is provided with a groove 26 so that a screw-driver, or other tool, can be applied to the nozzle to rotate it in boss 23 to adjust the discharge end of the nozzle inwardly or outwardly. By thus adjusting the nozzle, its inner end may be positioned closer or more remotely from the inner margin of the line of rest of the column of sand in the trap-conduit to vary the rate of displacement of the sand from said column and its discharge through the delivery pipe 17. The outer end of the screw-threaded socket 25, in which the head 22 of the nozzle is held, is open at the outer side of the wall at the elbow of the trap-conduit so the nozzle can be inserted and removed.

An air chamber 27 is formed in the casing 10 outwardly of the socket 25. Air under pressure is supplied to the upper end of chamber 27 from

a pipe 28 which is usually connected to a suitable control valve. This pipe is connected to the casing by a union coupling 29 and a nipple 30 which is screw threaded into the wall 31 outwardly of the chamber 27. The duct 30^a in nipple 30 constitutes the inlet for air into the upper end of said chamber. This air supply connection and inlet duct 30^a are offset relatively to the socket 25 and nozzle. The chamber 27 forms a passage for conducting air from the offset air inlet to the nozzle. The offset of the inlet is sufficient to provide for access to the nozzle, without removal of the nipple 30 of the air supply connection.

A plug or closure 32 extends through, and is screw-threaded to, the outer wall 31 of chamber 27, substantially in axial alignment with nozzle 20 and the socket 25. The inner end of plug 32 is adapted to seat against the outer face of the inner wall of chamber 27. A chamber 33 is formed in the inner end of plug 32. A small port 34 extends through the wall of plug 32 around chamber 33. This port restricts the flow of air under pressure from chamber 27 to the nozzle, so there will be a lower predetermined pressure in chamber 33, socket 25 and the cylinder bore 20^a in the nozzle. The restriction of the air by port 34 results in expansion of the air and reduction of the velocity of the blast which will cause the air to be delivered into the trap-conduit without concentration of the blast and cause it to be spread sufficiently to produce a substantially uniform delivery of the sand to the discharge pipe 17.

In operation, the air from pipe 28 under the engineer's control, will flow into chamber 27 and to port 34 in plug 32. Port 34 restricts the flow of air to chamber 33 in said plug, socket 25 and the bore of the nozzle, so the air will discharge the sand at the desired rate for sanding. The rate of delivery of air may be decreased by adjusting the nozzle inwardly or outwardly to vary the delivery of sand to the desired rate. Under different conditions it is desirable to increase or decrease the rate of the delivery of the sand for efficiency and economy in the use of the sand. For this purpose, it is desirable to readily effect and expedite adjustment of the nozzle without uncoupling the air supply connection from the sand-trap. In order to provide access to the nozzle it is only necessary to unscrew the plug 32 from the casing so the engineer can insert a screw-driver, or other tool, into the groove 26 in the outer end of the nozzle and turn the nozzle to set it for the desired rate of flow. Upon replacement of the plug 32 in wall 31, the sander will again be operative. In sand-traps of this type, as heretofore constructed, it has been necessary to uncouple the air supply pipe from the trap in order to provide access to the nozzle. By offsetting the air connection with respect to the opening for access to the nozzle, as described, and providing a removable closure or plug to provide access to the nozzle, changes in the adjustment of the nozzle can be easily and quickly effected independently of the air-supply connection. When the plug 32 is removed, the port 34 will be accessible for cleaning, if that becomes necessary. If it is desired to vary the restriction of flow of air, a plug 32 with a different size port 34 can be readily substituted without uncoupling the air supply pipe from the trap.

In the modified form of the invention illustrated in Figs. 5 and 6, the casing 10^a is of the same construction already described, except that

the trap-conduit has connected thereto a downwardly extending outlet 17^a to which the sand discharge pipe 17^b is connected and the air delivery pipe 19^a is connected to an angular downwardly discharging duct 18^a for delivering clean-out blasts into the upper end of the delivery pipe 17^b. The connection between air-supply pipe 28 and the casing, and the air-chamber 27 are the same as those already described. The screw-plug 32^a closes the opening in wall 31 but does not extend across chamber 27 so that a full flow of air will pass to the nozzle. In this modification a core is fitted in the nozzle and is provided with means for restricting the air-flow from the nozzle and with means for imparting a swirling movement to the air which issues from the nozzle. This core comprises a head 41 which is threaded to screw-thread 42 in the nozzle, and has a cylindrical portion 43 fitting in the outer end of the bore 20^d of the nozzle, and a stem 40. A port 43 extends from the outer end of the core to a port 44 which opens into the space in the bore around the stem 40. A helical flight 45 is formed on the stem 40 commencing near the outer end and terminating adjacent the inner end of the stem to form a helical channel between the stem and the bore of the nozzle, so that the air will flow from the helical channel around stem 40 and be discharged in a swirling stream from the inner end of the nozzle. In this modification, the nozzle can be adjusted or removed when plug 32^a is unscrewed from the casing.

The invention exemplifies a sand-trap in which the air delivery nozzle for discharging sand from the trap-conduit can be adjusted without removal or disturbing the connection for the air supply line with the sand trap. It also exemplifies a plug for providing access to the nozzle for adjustment thereof which is provided with means for restricting the air flow. It also exemplifies a device in the nozzle for restricting the air-flow discharged from the nozzle into the trap-conduit without the use of extremely small ports.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In a track sander, the combination of a casing provided with a vertically extending inlet leg for sand, a trap-conduit extending laterally from the inlet leg, and an outlet leading from one end of the conduit, the casing being provided with integral inner and outer walls forming therebetween a vertically extending elongated chamber at one side of and adjacent to the inlet leg and a tubular inward extension integral with the inner wall and having a screw-threaded socket therein, a nozzle-pipe extending longitudinally of the trap-conduit, having its outer end screw-threaded to and terminating in the socket in the tubular extension for longitudinal adjustment and its inner end projecting into the laterally extending trap-conduit, a plug at one end of said chamber coaxial with the nozzle-pipe, screw-threaded to the outer wall of said chamber for providing access to the nozzle-pipe, the inner end of the plug being seated on the outer face of the inner wall and having a port therein for admitting air to the socket, and a connection at the other end of the chamber in

offset relation to the plug, connected to said outer wall, for supplying air to the chamber.

2. In a track sander, the combination of a longitudinal trap conduit casing provided with sand, the casing being provided with a screw-threaded socket in a wall thereof, a nozzle-pipe extending longitudinally of the trap-conduit, having its outer end screw-threaded to and terminating in the socket for longitudinal adjustment and its inner end projecting into the trap-conduit, and a core screw-threaded to the inside bore of the nozzle-pipe and provided with a helical flight fitting in the bore of the nozzle-pipe and a port leading from its inner end to the helical channel formed by the flight.

3. In a track-sander, the combination of a casing provided with a vertically extending inlet leg for sand, a trap-conduit extending laterally from the inlet leg and an outlet leading from one end of the conduit, the casing being pro-

vided with integral inner and outer walls forming therebetween a vertically extending elongated chamber at one side of and adjacent to the inlet leg, the inner wall having a screw-threaded socket therein, a nozzle-pipe extending longitudinally of and having its inner end projecting into the trap-conduit and having its outer end screw-threaded to and terminating in the socket inwardly of the outer side of the inner wall for longitudinal adjustment of its inner end in the trap chamber, a plug at one end of said chamber coaxial with and for providing access to the nozzle-pipe, screw-threaded to the outer wall of said chamber, seated against the inner wall and provided with a port for admitting air from the chamber to the socket, and a connection at the upper end of said chamber in off-set relation to the plug and connected to said inner wall, for supplying air to the chamber.
